UNITED STATES PATENT OFFICE.

WILLIAM H. RYER, OF SALT LAKE CITY, UTAH TERRITORY, ASSIGNOR TO
MILLER, METCALF & PARKIN, OF PITTSBURG, PENNSYLVANIA.

DESIGN FOR A PAPER-WEIGHT.

SPECIFICATION forming part of Design No. 19,222, dated July 23, 1889.

Application filed June 27, 1889. Serial No. 315,820. Term of patent 14 years.

To all whom it may concern:

Be it known that I, WILLIAM H. RYER, a citizen of the United States, residing at Salt Lake City, in the county of Salt Lake and Territory of Utah, have invented and produced a certain new and original Design for Paper-Weights, of which the following is a specification.

The invention described herein relates to a certain new and original design for paper-weights.

In the accompanying drawings, forming a part of this specification, Figure 1 is a view in elevation of a paper-weight embodying my invention, and Fig. 2 is a plan view of the same.

The lower portion or base of the weight has a series of vertical ribs 2 and intermediate grooves 3. The stem or handle 4 is polygonal in cross-section. 20

The leading or characteristic features of my design are a star-shaped base or lower portion and a polygonal stem or handle.

I claim herein as my invention—

The design for a paper-weight, as herein shown and described. 25

In testimony whereof I have hereunto set my hand and seal.

WILLIAM H. RYER. [L. S.]
